(57) **CLAIM**

The ornamental design for a discharge portion of a liquid filament dispensing valve, as shown and described.

DESCRIPTION

FIG. 1 is a bottom perspective view of the discharge portion of a liquid filament dispensing valve illustrated as a first embodiment of the invention;

FIG. 2 is a front view of FIG. 1, the rear view being the same as the front view;

FIG. 3 is a right side view of FIG. 1;

FIG. 4 is a left side view of FIG. 1;

FIG. 5 is a top view of FIG. 1;

FIG. 6 is a bottom view of FIG. 1;

FIG. 7 is a bottom perspective view of an alternative embodiment of the invention;

FIG. 8 is a front view of FIG. 7, the rear view being the same as the front view of FIG. 7;

FIG. 9 is a right side view of FIG. 7;

FIG. 10 is a left side view of FIG. 7;

FIG. 11 is a top view of FIG. 7; and,

FIG. 12 is a bottom view of FIG. 7.

The elements shown in dash-dot lines form no part of the claimed invention, and are instead included to show environmental aspects of the claimed invention.
